UNITED STATES PATENT OFFICE.

ERNEST JAMES SMITH, OF CHICAGO, ILLINOIS, ASSIGNOR TO THE GOSS PRINTING PRESS COMPANY, OF CHICAGO, ILLINOIS, A CORPORATION OF ILLINOIS.

PRINTING-PRESS.

1,272,136.

Specification of Letters Patent.

Patented July 9, 1918.

Application filed June 19, 1916. Serial No. 104,467.

To all whom it may concern:

Be it known that I, ERNEST JAMES SMITH, a subject of the King of England, and a resident of Chicago, in the county of Cook, 5 State of Illinois, have invented certain new and useful Improvements in Printing-Presses, of which the following is a specification, reference being had to the accompanying drawings.

10 My invention relates to printing presses and it has for one of its objects to provide new and improved means automatically effective upon the breaking of the web of paper being printed to throw the press out 15 of operation relative to the driving means. It is another object of my invention to provide, in a press comprising a plurality of printing couples acting upon separate webs, means for driving the several printing 20 couples independently of the remainder of the press, so that when a single web breaks the proper one of the printing couples may be driven independently for rethreading the broken web whereby there may be a minimum wastage of paper as a result of the 25 break of the web. It is another object of my invention to provide a new and improved form and arrangement of means for throwing the press into slow speed operation and 30 then into high speed operation at the desired moment. It is another object of my invention to provide a new and improved form and arrangement of starting and stopping means for the press comprising a 35 suitable brake adapted to act upon the press independently of the driving motor. It is another object of my invention to improve presses of this type in sundry details hereinafter pointed out. The preferred means 40 by which I have accomplished my several objects are illustrated in the drawings and are hereinafter specifically described. That which I believe to be new and desire to cover by this application is set forth in the claims.

45 In the drawings:

Figure 1 is a view of a part of a press embodying my improvements;

Fig. 2 is a horizontal cross-section taken on line 2-2 of Fig. 1, showing the arrangement of the variable speed driving mechanism;

Fig. 3 is a vertical cross-section of the variable speed driving mechanism, being taken substantially on line 3-3 of Fig. 2;

Fig. 4 is a vertical cross-section taken on line 4-4 of Fig. 2;

Fig. 5 is an enlarged detail, being a fragmentary view showing the driving connections of the auxiliary motor;

Fig. 6 is an enlarged detail showing the arrangement of the switch controlled by the web of paper, adapted to be closed automatically for stopping the press upon the breakage of the web at any time during the full-speed operation of the press; and

Fig. 7 is a vertical cross-section on line 7-7 of Fig. 6.

Referring to the several figures of the drawings in which corresponding parts are indicated by the same reference characters,

10 indicates the framework of a press comprising longitudinally-extending frame bars 11 and 12, and a transversely-extending frame bar 13. Two sets of printing 75 mechanisms are shown in the drawings, one set comprising impression cylinders 14-15 and form cylinders 16-17, and the other set comprising impression cylinders 18-19 and form cylinders 20-21. As is indicated 80 by the showing of Fig. 3, each of the impression cylinders and form cylinders is provided with a suitable driving gear 22 at one end, the several gears 22 of each set of printing devices being in mesh in series with each 85 other and with gears 23 and 24 so as to be properly driven, the gears 24 being fixed upon shafts 25-26, respectively, suitably mounted on the framework 10. Any suitable type of inking mechanism is adapted to 90 be used, and inasmuch as such inking mechanism forms no part of the present invention it is not believed to be necessary to illustrate or describe it.

Means is provided for rotating the shafts 95 25-26 at variable speeds either separately or in unison. This means comprises bevel gears 27-28 mounted upon the shafts 25-26, respectively, meshing with bevel gears 29-30 revolubly mounted upon a vertical shaft 31. The gear 29 has fixedly connected with it a gear 32 and a clutch mem-

ber 33 which is adapted to be driven by a coöperating clutch member 34 mounted upon the shaft 31 so as to rotate therewith but so as to be slidably longitudinally thereof into 5 engagement with the clutch member 33 or out of engagement therewith against the action of a spring 35. The bevel gear 30 has rigidly connected with it a gear 36 and a clutch member 37, which is adapted to 10 be driven by a coöperating clutch member 38 which is mounted upon the shaft 31 so as to rotate therewith but so as to be movable longitudinally thereof into engagement with the clutch member 37 or out of engagement therewith against the action of a spring 39. With the clutch members 34-38 in operative engagement with the coöperating clutch members 33-37, and with the shaft 31 being driven in clockwise direction 15 in Fig. 2, the printing couples are adapted to be driven in a direction for carrying the webs 40-41 through the printing couples as indicated by the arrows upon the webs in Fig. 1.

25 The means for driving the shaft 31 comprises a motor 42 connected with a short transversely-extending shaft 43. A pinion 44 on the shaft 43 meshes with a gear 45 fixed upon a sleeve 46 revolvably mounted 30 upon a transversely-extending shaft 47. Fixed upon the sleeve 46 is a pinion 48 which meshes with a gear 49 fixed upon a sleeve 50 revolvably mounted upon a shaft 51, which, in the construction shown, is in 35 alignment with the shaft 43. Fixed upon the sleeve 50 (see Fig. 4) is a ratchet wheel 52 which is adapted through the medium of three pawls 53 to drive a drum 54 in clockwise direction in said Fig. 4. The drum 54 is adapted to be connected by means of a 40 clutch mechanism 55 of any suitable type with the shaft 51 for causing the drum and the shaft to rotate together, the clutch mechanism 55, in the construction shown, comprising levers 56 which are adapted to 45 be spread apart for clutching the drum 54 to the shaft 51 by a movement of a head 57 longitudinally of the shaft 51 toward the drum, as hereinafter described. Motion is 50 transmitted from the shaft 51 to the shaft 47 by means of a pinion 58 fixed upon the shaft 51 and meshing with a gear 59 fixed upon the shaft 47. Motion is transmitted 55 from the shaft 47 to the shaft 31 by means of intermeshing bevel gears 60-61. By reason of the relative sizes of the intermeshing gears 44-45, 48-49, and 58-59, the shaft 31 is driven at a comparatively very slow speed as compared to that of the motor 42, being designed to be driven at a speed of ten to twenty revolutions per minute as compared to 500 or a 1000 revolutions per minute for the motor.

60 Means is provided for connecting the gear 65 directly with the shaft 47 whenever de-

sired, such means comprising a clutch mechanism 62 comprising arms or levers 63 adapted to be spread apart by a longitudinal movement of a head 64 slidably mounted upon the shaft 47 for connecting the clutch member 62 with the shaft. With the shaft 47 being driven at low speed by the gear 45 through the medium of the gears 48 and 49, the clutch 55, the shaft 51 and the gears 58-59, the clutch 62 may be 75 thrown into operation by a longitudinal movement of the head 64 causing the shaft 47 to rotate at comparatively high speed with the gear 45 and the clutch mechanism 62. This action serves to rotate the shaft 51 at a comparatively very high speed relative to the speed of the gear 49, the pawls 53 being adapted to slip over the teeth of the ratchet 52 for this purpose. With the clutch member 55 rotating at high speed 80 with the shaft 51, the pawls 53 are adapted to be thrown by centrifugal force out of mesh with the teeth of the ratchet wheel 52, making it unnecessary to throw the clutch 85 55 out of operation.

90 Means is provided for moving the heads 57-64 longitudinally of the shafts 51-47 respectively for throwing the clutch members 55 and 62 into and out of operation in proper timed relation to each other. The head 57 is adapted to be moved longitudinally by means of a yoke 65 engaging a suitable circumferential groove in the head 57, said yoke being pivotally mounted upon a bracket 66 extending laterally from the frame 95 bar 11. The yoke 65 is operated by an arm 67 provided with a roller 68 at its upper end working in a suitable cam groove in a cam member 69 fixed upon a shaft 70 extending transversely of the press. The head 100 64 is adapted to be moved longitudinally through the medium of a yoke 71 the lower ends of which engage a suitable groove in the said head 64. The yoke 71 is pivotally mounted upon a bracket 72 extending transversely from the frame bar 12 (see Fig. 3). The yoke 71 is operated by an arm 73 provided at its upper end with a roller 74 engaging a suitable cam groove in a cam member 75 also fixed upon the shaft 70. As will 105 be seen from an inspection of Figs. 2 and 3, when the shaft 70 is given approximately a quarter of a revolution in counter clockwise direction in Fig. 1 from the position shown in Fig. 2, the clutch member 64 is 110 not affected by reason of the dwell in the cam groove in the cam member 75, but such rotation of the shaft 70 serves to throw the clutch 57 into operation, serving to drive at 115 low speed. Upon the next-succeeding quarter revolution of the shaft 70 in the same direction, the clutch 64 is thrown into operation, serving to drive the shaft 47 at high speed. Upon a rotation of the shaft 70 in the opposite direction, the high speed clutch 62 is 120 125 130

first thrown out of operation, and in due time the low speed clutch 55 is thrown out of operation, bringing the apparatus to the condition shown in Fig. 2. Upon a still further rotation of the shaft 70 in clockwise direction in Fig. 1, a brake-band 76 is tightened about a brake-drum 77 mounted upon the shaft 51, this effect being attained through the medium of a lever 78 and a link 79 having an eccentric connection at its upper end with the shaft 70. By means of this brake the press is gradually slowed down and stopped independently of the rotation of the heavy motor 42.

In the construction shown means is provided for rotating the shaft 70 for controlling the clutch mechanisms 55 and 62 and the brake 76, comprising a motor 80 connected with the shaft 70 by means of a worm 81 and worm-gear 82, as is best shown in Fig. 5. The motor 80 is preferably provided with controller means by which the motor is automatically thrown out of operation when the shaft 70 has been given a quarter turn for throwing the clutch mechanism 57 into operation. When the press has been driven at a slow speed for the desired period of time, and the motor 80 has been again thrown into operation for rotating the shaft 70 still further for throwing the clutch mechanism 62 into operation, the controller means preferably serves to throw the motor 80 out of operation promptly after the clutch 62 has been thrown into operation. When the motor 80 has been set into operation for turning the shaft 70 in a direction for throwing the clutch mechanisms 62 and 55 out of operation, the controller system preferably serves to maintain the motor 80 in operation until after both clutches have been thrown out and the brake has been set, whereupon the motor 80 is automatically stopped.

The controller system for the motor 80 comprises a circuit 83 including a battery 84 or other suitable source of electric current. The circuit 83 is so arranged in connection with its co-operating controlling parts that upon the closing of the circuit the motor 80 is set in operation in such direction as to throw the clutches 55 and 62 out of operation and to set the brake 76. The circuit 83 is provided with a switch which is adapted to be automatically closed at the time the clutch mechanism 62 is thrown into operation for running the press at high speed and is to be automatically opened when the clutch 62 is thrown out of operation at the end of the high speed driving. This switch comprises two contacts 85-86 (see Fig. 2) spaced apart and connected with the circuit wires 83. The space between the contacts 85-86 is adapted to be bridged by a movable switch member 87 connected with the yoke 71 of the operating mechanism for the clutch 62, the arrangement being such that when the head 64 is moved in the direction to throw the clutch 62 into operation the switch 85-86 is closed and that when the head 64 is moved in the opposite direction for throwing the high speed clutch 62 out of operation the switch 85-86 is opened.

The circuit 83 is also provided with a plurality of other switch devices 88 connected in parallel across the circuit. Each of these switches comprises contact members 89-90 connected with the circuit wires, adapted to be moved into contact with each other for closing the switch by an upward movement of a pin 91 (see Fig. 6). The pins 91 are adapted to be moved upward for closing the switches by means of arms 92 pivotally mounted upon the frame 10 carrying at their ends transversely-extending rollers 93 which during the normal operation of the press are supported by the webs 40-41 in conjunction with suitable springs 94. As will be readily understood, in case either of the webs 40-41 should break during the operation of the press at high speed, the corresponding roller 93 would move down suddenly against the action of the spring 94, serving to push upward the pin 91 of the adjacent switch 88 serving to close the circuit 83 for throwing the motor 80 into operation for stopping the press. In case the web should break during the operation of the press at low speed, the closing of the switches 88 would have no effect, inasmuch as the circuit would already be broken between the contacts 85-86, as above described. Means is provided for holding the rollers 93 independently of the webs 40-41 normally in raised position so as to hold the arms 92 out of contact with the pins 91. This means comprises pins or lugs 95 carried by the arms 92 (see Fig. 7) adapted to engage spring-seated pins 96 carried by the framework 10. The strength of the springs 97 against which the pins 96 bear is designed to be such that when the pin 95 is brought easily and slowly into contact with the pin 96 the arm 92 is held against further movement, serving thus to hold the arms 92 out of contact with the pins 91. The springs 97 are of such strength, however, that when the pins or lugs 95 are brought suddenly and sharply into contact with the pins 96, as is the case when the web breaks, the springs 97 yield so as to permit the arms 92 to pass for closing the controller circuit 83 as above described.

Means is provided for rotating the shaft 70 if desired independently of the power generated by the motor 80, comprising a hand-wheel 98 by which the motor shaft may be turned manually for the desired rotation of the shaft 70. As will be readily

understood from an inspection of Fig. 5, the handwheel 98 may be readily lifted out of engagement with the motor 80 whenever desired.

5 Means is provided for driving the press at slow speed independently of the rotation of the shaft 31. This means comprises a large gear 99 mounted upon a shaft 100 and meshing with the pinion 48, the gear 99 and the 10 shaft 100 being thus adapted to be driven continuously at low speed independently of the clutch mechanisms 55 and 62. The shaft 100 is provided with a bevel gear 101 which meshes with a gear 102 mounted upon a vertical shaft 103. Mounted upon the shaft 103 are two gears 104—105 meshing with the gears 36—32 respectively. The gears 104—105 are normally free to rotate relative to the shaft 103 but are adapted to be 15 connected with said shaft for rotation thereby by means of clutch members 106—107, respectively. The clutch members 106—107 are adapted to be thrown into operation by longitudinal movement of heads 108—109 20 along the shaft 103 by any suitable means, serving to spread apart the levers 110 of the clutch members 106—107. With the shaft 31 at rest and with the shaft 103 being driven at low speed, either the clutch 25 member 34 or the clutch member 38 may be moved upward by any suitable means and the adjacent clutch mechanism 107 or 106 can be thrown into operation, serving to drive at low speed either the printing couple 30 comprising the cylinders 18, 19, 20 and 21 or the printing couple comprising the cylinders 14, 15, 16 and 17.

Means is provided for controlling the position of the clutch member 38 and the clutch 40 operating head 108, comprising two bell-crank levers 111—112, one arm of each of said levers being in the form of a yoke having operative engagement with one of the clutch members. The levers 111—112 are 45 adapted to be given any adjustment as desired relative to each other by means of an adjusting slot 113. By a stroke of the lever 112 to the left in Fig. 1 from the position shown therein, the clutch member 38 may be 50 thrown into engagement with the clutch member 37 whereby the lower printing couple is adapted to be driven through the medium of the shaft 31 at either high speed or low speed. By a movement of the lever 112 55 to the right in Fig. 1, the clutch mechanism 106 may be thrown into operation for driving the said lower printing couple at low speed independently of the rotation of the shaft 31. By reason of having the clutch 60 member 38 and the clutch operating head 108 controlled by the same set of devices, the danger of having both clutches thrown into operation at the same time is kept at a minimum. Levers 114—115 are adjustable relative to each other by means of a slot 116 and

are provided for controlling in like manner the movements of the clutch member 34 and the clutch operating head 109.

By the use of the mechanism above described, whenever during the normal operation of the press one of the webs breaks, the entire press is promptly brought to a stop without any change in the operation of the driving motor 42, this being effected through the action of the controller system comprising the circuit 83 closed by one of the switch devices 88 upon the breaking of the web. When the press has been brought to a stop, the clutch by which the shaft 31 is connected with the printing couple acting upon the web 75 which has broken may be thrown out of operation manually and the corresponding clutch 106 or 107 may be thrown into operation, serving to drive such printing couple at its low speed. When the web has been 80 again threaded through this printing couple, the clutches may be again shifted manually to a proper condition for normal high speed operation of the press and the operation of the press through the shaft 31 may be resumed. By the provision of means for driving a single printing couple at slow speed by itself independently of the remainder of the press, it is rendered unnecessary to drive the whole press at slow speed for rethreading a single printing couple, making possible thus a very material saving of paper.

As will be seen by an inspection of Fig. 1, the engaging faces of the clutch members 33—34 and the engaging faces of the clutch members 37—38 are so disposed relative to each other that the upper one of each pair of coöperating clutch members has a tendency to prevent the lower member from running ahead. Thus when the brake 76 is applied to the shaft 51 and the shaft 31 is thus slowed down and brought to a stop, the effect of the brake is transmitted through the coöperating clutch members 38—37 and 90 34—33 to the printing couples.

As will be appreciated from the above description, when the motor 80 has been automatically set into operation through the breaking of a web for disconnecting the press from the motor 42, the high speed 105 clutch 62 is quickly thrown out of operation serving thus to open the circuit 83 by the movement of the switch member 87. The means for disconnecting the motor 42 from the printing couple, comprising the motor 110 80 and its coöperating parts, is thus rendered inoperative or ineffective as to any subsequent disconnecting operation until after the high speed clutch 62 has been again thrown into operation. This inoperativeness of the motor 80 and its coöperating parts produced by the opening of the circuit 83 when the high speed clutch 62 is thrown out of operation is not effective as to the disconnecting operation already started 125 130

but becomes effective as to subsequent disconnecting operations immediately upon the completion of the disconnecting operation already started.

5. What I claim as my invention and desire to secure by Letters Patent, is—

1. In a web printing press, the combination of a printing couple, a motor, clutch connections between said motor and said 10 printing press, a second motor, means operable by said second motor for throwing said clutch connections out of operative engagement, and means effective upon the breaking of the web being printed for throwing said 15 second motor into operation.

2. In a web printing press, the combination of a printing couple, a motor, clutch connections between said motor and said printing press, a second motor, means for 20 throwing said clutching connections out of operation, a brake for stopping said printing couple, means for operatively connecting said motor with said clutch operating means and with said brake, and means effective upon the breaking of the web being 25 printed for throwing said second motor into operation.

3. In a web printing press, the combination of a printing couple, a motor, clutch 30 connections between said motor and said printing press, a second motor, means for throwing said clutching connections out of operation, means for operatively connecting said second motor with said clutch operating 35 means, and means effective upon the breaking of the web being printed for throwing said second motor into operation.

4. In a web printing press, the combination of a printing couple, a motor, clutch 40 connections between said motor and said printing press, means for throwing said clutching connections out of operation, a second motor, means for operatively connecting said second motor with said clutch operating 45 means, a controller system for said second motor comprising an electric circuit provided with a switch by the operation of which said second motor is set into operation, and means effective upon the breaking 50 of the web being printed for operating said switch for throwing said second motor out of operation.

5. In a web printing press, the combination of a printing couple, a motor, clutch 55 connections between said motor and said printing press, means for throwing said clutching connections out of operation, a second motor, means for operatively connecting said second motor with said clutch 60 operating means, a controller system for said second motor comprising an electric circuit provided with a plurality of switches connected in parallel across the circuit, by the closing of any one of which switches said 65 second motor is set into operation, and

means effective upon the breaking of the web being printed for closing one of said switches.

6. In a printing press, the combination of a plurality of printing couples, a motor, 70 clutching connections between said motor and said printing couples, means for throwing said clutching connections out of operation, a second motor, means for operatively connecting said second motor with said clutch operating means, a controller system for said second motor comprising an electric circuit provided with a plurality of switches by the operation of any one of which said second motor is set into operation, and means effective upon the breaking of the web being printed by any one of said printing couples for operating one of said switches to throw said second motor out of 75 operation.

7. In a web printing press, the combination of a printing couple, a motor, clutch connections between said motor and said printing press, and means automatically effective when the press is operating at its 80 high speed to move said clutching connections out of operative engagement upon the breaking of the web being printed, and means for rendering said automatically-acting clutch-moving means ineffective upon a 85 break of the web when the press is operating at its low speed.

8. In a web printing press, the combination of a printing couple, a motor, variable 90 speed connections between said motor and said printing couple, and means automatically effective when said printing couple is being driven at its high speed by said motor for stopping the operation of the printing couple upon the breaking of the web being 95 printed but adapted to permit a break of the web upon the low speed operation of the printing couple without affecting the operation of the printing couple.

9. In a web printing press, the combination of a printing couple, a motor, variable speed connections between said motor and said printing couple, means for shifting said variable speed connections for varying the speed of driving, and means thrown into operation upon the shifting to high speed and thrown out of operation upon the shifting to low speed effective at the high speed operation of the printing couple to stop the operation of the printing couple upon the 110 breaking of the web being printed.

10. In a web printing press, the combination of a printing couple, a motor, variable speed mechanism connecting said motor with said printing couple, comprising a high speed clutch adapted when in operation to drive said printing couple at its high speed, means automatically effective at the high speed operation of the printing couple 115 to stop the operation of the printing couple 120

upon the breaking of the web being printed, and means adapted for throwing said high speed clutch and said automatically-acting stopping means simultaneously out of operation.

11. In a web printing press, the combination of a printing couple, a motor, variable speed mechanism connecting said motor with said printing couple, comprising a high speed clutch adapted when in operation to drive said printing couple at its high speed, means automatically effective upon the breaking of the web being printed when the printing couple is being driven at its high speed to disconnect said motor from said printing couple, and means for throwing said high speed clutch out of operation and at the same time rendering said disconnecting means ineffective whereby a break 20 of the web at low speed does not stop the printing couple.

12. In a web printing press, the combination of a printing couple, a motor, variable speed mechanism connecting said motor with said printing couple, comprising a high speed clutch and a low speed clutch, means automatically effective when the printing couple is being driven at its high speed to throw both of said clutches out of 30 operation upon the breaking of the web being printed, and means serving upon the throwing of the high speed clutch out of operation to render said automatically-acting clutch throwing means ineffective 35 whereby a break of the web at low speed shall not stop the printing couple.

13. In a web printing press, the combination of a printing couple, a motor, and connections, between said motor and said printing couple adapted to drive the printing couple at a variable speed, comprising a shaft through which said printing couple is driven at its low speed, means for braking the rotation of said shaft, and means effective when the printing couple is being driven at its high speed to act automatically, upon the breaking of the web being printed, to bring the printing couple to its low speed operation, then to disconnect said shaft 50 from said motor, and then to apply the brake upon said shaft.

14. In a web printing press, the combination of a printing couple, a motor, and connections between said motor and said printing couple adapted to drive the printing couple at a variable speed, comprising a shaft, means for braking the rotation of said shaft, a high speed clutch, a low speed clutch, and means effective when the printing couple is being driven at its high speed to act automatically, upon the breaking of the web being printed, to throw said high speed clutch out of operation, then to throw said low speed clutch out of operation, and 65 finally to set said brake.

15. In a web printing press, the combination of a printing couple, a motor, means for connecting said printing couple intermittently with said motor, means actuated independently of said motor effective automatically during the high speed operation of the printing couple to disconnect said motor from said printing couple upon the breaking of the web being printed, and means for throwing said disconnecting means out of operation when the printing couple is brought from its high speed operation to its low speed operation independently of a break of the web.

16. In a web printing press, the combination of a printing couple, a motor, means for connecting said printing couple intermittently with said motor, a second motor adapted upon a break of the web being printed to disconnect said first-named motor from said printing couple, a controller system for said second motor comprising an electric circuit provided with a switch by the opening of which said second motor is thrown out of operation, and means for automatically opening said switch when the printing couple is brought from high speed to low speed operation.

17. In a web printing press, the combination of a printing couple, a motor, means for connecting said printing couple intermittently with said motor, a second motor adapted upon a break of the web being printed to disconnect said first-named motor from said printing couple, a controller system for said second motor comprising an electric circuit provided with a switch by the opening of which said second motor is thrown out of operation, and means for automatically closing said switch when the printing couple is brought from low speed to high speed operation and for automatically opening the switch when the printing couple is brought from high speed to low speed operation.

18. In a web printing press, the combination of a printing couple, means for driving said printing couple for printing a web thereby, a roller adapted normally to be supported by said web but adapted to descend upon the breaking of the web, and yielding means adapted to support said roller above its lowermost position when the roller is moved downward easily into engagement but adapted to permit the roller 120 to move to its lowermost position when the roller is moved downward into engagement with a sudden sharp movement.

19. In a web printing press, the combination of a printing couple, means for driving said printing couple for printing a web thereby, a roller adapted normally to be supported by said web but adapted to descend upon the breaking of the web, yielding means adapted to support said roller 130

above its lowermost position when the roller is moved downward easily into engagement but adapted to permit the roller to move to its lowermost position when the roller is moved downward into engagement with a sudden sharp movement, and an electric switch adapted to be operated by a downward movement of the roller beyond the position at which it is supported by said yielding means.

20. In a web printing press, the combination of a printing couple, means for driving said printing couple for printing a web thereby, a roller adapted normally to be supported by said web but adapted to descend upon the breaking of the web, and a spring-seated pin adapted to support said roller above its lowermost position when the roller is moved downward easily into engagement but adapted to permit the roller to move to its lowermost position when the roller is moved downward into engagement with a sudden sharp movement.

21. In a web printing press, the combination of a printing couple, means for driving said printing couple for printing a web thereby, a roller adapted normally to be supported by said web but adapted to descend upon the breaking of the web, yielding means adapted to support said roller above its lowermost position when the roller is moved downward easily into engagement but adapted to permit the roller to move to its lowermost position when the roller is moved downward into engagement with a sudden sharp movement, an electric switch adapted to be closed by a downward movement of the roller beyond the position at which it is supported by said yielding means, and means set into operation by the closing of said switch upon the breaking of the web for disconnecting said printing couple from its driving means.

22. In a printing press, the combination of a printing couple, a driving shaft, variable speed mechanism for connecting said shaft with said printing couple, comprising a low speed clutch and a high speed clutch, and means connected with both of said clutches adapted by a movement in one direction to throw them successively into operation.

23. In a printing press, the combination of a printing couple, a driving shaft, variable speed mechanism for connecting said shaft with said printing couple, comprising a low speed clutch and a high speed clutch, and means adapted by a movement in one direction to throw said low speed clutch into operation and then to throw said high speed clutch into operation, and adapted alternatively by movement in the opposite direction to throw said clutches successively out of operation in the reverse order.

24. In a printing press, the combination

of a printing couple, a driving shaft, variable speed mechanism for connecting said shaft with said printing couple, comprising a low speed clutch and a high speed clutch, means for braking the rotation of the printing couple independently of the rotation of said shaft, and means connected with both of said clutches adapted to throw said high speed clutch out of operation, then to throw said low speed clutch out of operation, and then to apply said braking means.

25. In a printing press, the combination of a printing couple, a driving shaft, variable speed mechanism for connecting said shaft with said printing couple, comprising a low speed clutch and a high speed clutch, a second shaft, means for rotating said second shaft as desired, and cams actuated by the rotation of said second shaft in one direction to throw said clutches successively into operation and actuated by the rotation of said second shaft in the opposite direction to throw said clutches successively out of operation in the reverse order.

26. In a printing press, the combination of a printing couple, a driving shaft, variable speed mechanism for connecting said shaft with said printing couple, comprising a low speed clutch and a high speed clutch, a second shaft, means for rotating said shaft as desired, cam means mounted on said shaft and connected with said clutches respectively, means for braking the rotation of the printing couple independently of the rotation of said first-named shaft, an eccentric mounted on said second shaft, and connections between said eccentric and said braking means, the arrangement being such that upon the rotation of said second shaft in one direction said low speed clutch is thrown into operation and then said high speed clutch is thrown into operation, and upon the rotation of said second shaft in the opposite direction said high speed clutch and said low speed clutch are thrown successively out of operation and then the brake is applied for stopping the rotation of the printing couple.

27. In a printing press, the combination of a printing couple, a driving shaft, variable speed mechanism for connecting said shaft with said printing couple, comprising a low speed clutch and a high speed clutch, a second shaft, means for rotating said second shaft as desired, means actuated by the rotation of said second shaft in one direction to throw said clutches successively into operation and actuated by the rotation of the shaft in the opposite direction to throw said clutches out of operation in the reverse order, and means automatically effective upon the breaking of the web being printed to set said second shaft into operation for throwing said clutches out of operation.

28. In a printing press, the combination

- of a printing couple, a driving shaft, variable speed mechanism for connecting said shaft with said printing couple, comprising a low speed clutch and a high speed clutch, 5 a second shaft, a motor for rotating said second shaft as desired, means actuated by the rotation of said second shaft in one direction to throw said clutches successively into operation and actuated by the rotation of 10 the shaft in the opposite direction to throw said clutches successively out of operation in the reverse order, a controller system for said motor comprising an electric circuit provided with a switch by the closing of 15 which said motor is set into operation for throwing said clutches out of operation, and means automatically effective upon the breaking of the web being printed to close said switch.
- 20 29. In a printing press, the combination of a plurality of printing couples, a driving shaft, means operatively connecting said printing couples with said shaft for driving said printing couples in unison, and other 25 means adapted alternatively to connect one of said printing couples with said shaft for driving said printing couple at low speed independently of the rotation of said first-named driving connections.
- 30 30. In a printing press, the combination of a plurality of printing couples, a driving shaft, means operatively connecting said printing couples with said shaft for driving said printing couples in unison, and other 35 means adapted alternatively to connect any one or all of said printing couples with said shaft for driving at low speed independently of the rotation of said first-named driving connections.
- 40 31. In a printing press, the combination of a plurality of printing couples, a driving shaft, variable speed mechanism operatively connecting said printing couples with said shaft for driving said printing couples in 45 unison either at high speed or at low speed as desired, and other means adapted alternatively to connect one of said printing couples with said shaft for driving said printing couple at low speed independently 50 of the rotation of said variable speed mechanism.
32. In a printing press, the combination of a plurality of printing couples, a shaft adapted to be operatively connected with 55 said printing couples for driving them in unison, a second shaft adapted alternatively to be connected with one of said printing couples for driving it independently of the rotation of said first-named shaft, a motor, 60 low speed connections between said motor and said second shaft, and variable speed connections between said motor and said first-named shaft.
33. In a printing press, the combination 65 of a printing couple, means for driving said

printing couple, other means adapted to be used alternatively for driving said printing couple, a lever by a stroke of which said first-named driving means is thrown into operation, a second lever by a stroke of which said second-named driving means is thrown into operation, and connections between said two levers for preventing both of said driving means from being thrown into operation at the same time. 75

34. In a printing press, the combination of a printing couple, means for driving said printing couple, other means adapted to be used alternatively for driving said printing couple, a bell-crank lever by a stroke of which said first-named driving means is thrown into operation, a second bell-crank lever by a stroke of which said second-named driving means is thrown into operation, and adjustable connections between said two levers adapted normally to prevent both of said driving means from being thrown into operation at the same time. 80

35. In a printing press, the combination of a printing couple, a gear adapted to drive 90 said printing couple, a second gear meshing with said first-named gear, a motor, means for connecting said motor with said first-named gear through said second gear for driving at low speed, and other means for 95 connecting said motor with said first-named gear independently of said second gear for driving said first-named gear either at low speed or at high speed.

36. In a printing press, the combination 100 of a printing couple, a shaft, a gear revolvably mounted on said shaft and adapted by its rotation to drive said printing couple, clutching means for operatively connecting said gear with said shaft to rotate therewith, 105 a second shaft, a gear revolvably mounted on said second shaft and meshing with said first-named gear, clutching means for operatively connecting said second gear with said second shaft to rotate therewith, and 110 means for throwing either clutching means into operation as desired to the exclusion of the other.

37. In a printing press, the combination 115 of a printing couple, a shaft, a gear revolvably mounted on said shaft and adapted by its rotation to drive said printing couple, clutching means for operatively connecting said gear with said shaft to rotate therewith, 120 a second shaft, a gear revolvably mounted on said second shaft and meshing with said first-named gear, clutching means for operatively connecting said second gear with said second shaft to rotate therewith, a motor, means for driving said shafts at different speeds from said motor, and means 125 for throwing either clutching means into operation as desired to the exclusion of the other.

38. In a printing press, the combination 130

of a printing couple, a shaft, a gear revolvably mounted on said shaft and adapted by its rotation to drive said printing couple, clutching means for operatively connecting said gear with said shaft to rotate therewith, a second shaft, a gear revolvably mounted on said second shaft and meshing with said first-named gear, clutching means for operatively connecting said second gear with said second shaft to rotate therewith, 10 a motor, means for driving said first-named shaft at either high speed or low speed from said motor, means for driving said second shaft at low speed from said motor, and means for throwing either clutching means 15 into operation as desired to the exclusion of the other.

ERNEST JAMES SMITH.
